UNITED STATES PATENT OFFICE.

FRANK L. SESSIONS, OF COLUMBUS, OHIO, ASSIGNOR TO SIEMENS & HALSKE ELECTRIC COMPANY OF AMERICA, A CORPORATION OF NEW JERSEY.

CIRCUIT-BREAKER.

SPECIFICATION forming part of Letters Patent No. 762,204, dated June 7, 1904.

Application filed June 16, 1902. Serial No. 111,820. (No model.)

To all whom it may concern:

Be it known that I, FRANK L. SESSIONS, a citizen of the United States, residing at Columbus, in the county of Franklin and State of Ohio, have invented certain new and useful Improvements in Circuit-Breakers, of which the following is a specification.

My invention relates to improvements in electric switches of that class familiarly known as "circuit-breakers" and which are designed to automatically break or shunt the circuit in which the switch is connected whenever the volume of current flowing in the circuit exceeds a certain predetermined limit.

Among the objects of the invention are to provide at a minimum cost a construction which insures a very perfect and certain closing-contact between the main contacts—*i. e.*, a contact-extending throughout the full area of the contact-surfaces of said parts—to provide a switch having auxiliary carbon or equivalent contacts which constitute the final opening-points of the switch, and which contacts are so arranged and supported as to insure a more perfect yielding contact with each other than has heretofore been attained in similar switches; to provide a construction in which by the change or substitution of a single part the capacity of the switch as determined by the amount of current which will operate to open the circuit may be varied at will within reasonable limits; to provide improvements in the details of construction of the switch rendering it economical to manufacture and at the same time durable and reliable, and in general to provide a simplified and improved device of the character referred to.

The invention consists in the matters hereinafter described and more particularly pointed out in the appended claims and will be more readily understood by reference to the accompanying drawings, in which—

Figure 1 is a plan view of a switch embodying my invention, the switch being shown in closed position. Fig. 2 is a side elevation of the same, a part of the handle being broken away to reduce the size of the figure. Fig. 3 is a rear end elevation of the switch shown

in Figs. 1 and 2, drawn on a larger scale. Fig. 4 is a transverse sectional view of the 50 solenoid looking toward the front end of the switch. Fig. 5 is a side elevation of one of the interchangeable conductor-bars having a larger current-carrying capacity than that shown in position upon the switch. Fig. 6 is 55 a perspective view of one of the laminated contact devices. Fig. 7 is a sectional view of details hereinafter described. Fig. 8 is a detail perspective of part of the devices for yielding and oscillating supporting the contact- 60 plates carried by the base-block.

Referring to said drawings, A designates a base-plate of insulating material upon which are mounted two contact-supporting plates B B', arranged in the present instance parallel 65 with each other at a considerable distance apart, so as to extend longitudinally of the base-plate and permanently secured to the base by screws, as usual. Each of said contact-supporting plates is provided at one end 70 (for convenience of description hereinafter designated the "front" end) with a slightly-elevated flat seat b, as shown most clearly in Fig. 2. Upon each of said seats b is mounted a contact device C, consisting of a plurality 75 of thin leaves or laminae b' superposed upon each other and secured rigidly upon the seat by means of screws or bolts b'', inserted through plates b', arranged to overlie the front end of each contact device, passing through said 80 leaves and threaded into the contact-supporting plate beneath. The length of each of the leaves constituting the contact device is greater than the length of the seat upon which they are mounted, and they are so arranged thereon that their rear ends project 85 freely beyond the seat, so that the rear end of the contact device as a whole is capable of yielding downwardly under pressure. In order to afford a suitable contact-surface for a 90 contact-bar which engages the contact devices in a manner hereinafter described, the projecting ends of the leaves are dressed off obliquely and made successively shorter from the lowermost upwardly to form a beveled 95 contact-surface b'.

D designates as a whole a double switch-lever standard, comprising two standard members d united by means of an integral yoke-shaped bar d' and secured rigidly upon the base a short distance in front of the contact-supporting plates b and at equal distance on each side of a line passing centrally between the said supporting-plates. Each standard member is provided at its rear side, near the upper end thereof, with a pivot-supporting ear d'' , which ears are provided with pivot-apertures arranged in alinement with each other.

E designates a switch-lever bifurcated or provided with arms e , adapted to fit between the ears d'' and pivotally secured thereto by means of pivot-pins d^3 . Said lever comprises an upwardly or outwardly extending member E' , provided with a suitable shank, to which is attached an insulating-handle E^2 , and with a rearwardly or downwardly extending member E^3 , provided with laterally-extending lugs or supports e' , to which is attached a transversely-extending contact-bar E^4 of suitable length to extend across and engage both contacts C and having its lower surface arranged at a suitable angle to insure accurate contact with the beveled ends of the leaves forming said contacts C.

In order to prevent sparking between the contacts C and the contact-bar E^4 , the switch is provided with auxiliary or secondary carbon contacts constructed and arranged as follows: Referring to Fig. 3, F F designate carbon contacts, desirably and as shown herein having the form of flat plates or slabs of carbon, yieldably supported upon the plates BB', in electrical connection with the latter and arranged to stand in upright or outwardly-projecting position parallel or substantially parallel with each other. As a desirable means of supporting said carbon contacts in such manner as to permit them to yield laterally and at the same time to oscillate out of their normal planes to a certain extent supporting devices are provided, as follows: F' F' designate lugs or standards rigidly secured to the plates B B' and each provided at its upper part with a pivot-stud f , upon which is mounted an upwardly-extending arm f' , which is in turn pivotally engaged at its upper end with an ear or pivot-lug f'' , secured to the carbon plate at a point intermediate of the length or height of the latter and preferably about midway of its width. The upper or free end of the arm f' is normally pressed outwardly by means of a spring f^3 , desirably and as herein shown having the form of a U-shaped loop, the upper end of which rests against and embraces the upper end of the arm f' , while the lower ends are coiled one or more times around the pivot f and engaged with a part of the standard, so as to tend to force the arm f' outwardly. The lower ends of the carbons are each yieldably connected with the standards F' in such manner as to permit them to

approach the latter bodily conveniently by means of U-shaped springs f^5 , one arm of each of which is secured against the inner side of the carbon, while the opposite arm is provided with an end portion f^6 , which is bent at right angles and carried beneath the standard and rigidly held by the latter.

G designates an auxiliary switch-lever, which is also bifurcated or provided with arms g at its front end, arranged to embrace the outer sides of the pivot-ears d'' and engaged with the pivots d^3 of the latter. At its rear end said lever is provided with a transversely-extending bar G' , mounted thereon in a manner similarly to the connections between the lever E and bar E^4 , hereinbefore described, and carrying at each end a depending carbon contact-plate G^2 , adapted to respectively engage the contact-plates F. Conveniently the contact-plates G^2 are attached to the bar G' by means of L-shaped plates g' , one part of each of which embraces the outer surface of the contact-plate, while the other part, bent at right angles to the part embracing the plate, is carried beneath the bar G' and rigidly secured thereto by means of suitable screws or otherwise. The contact-plates are desirably made rigid with the supporting-plates g' by means of screws or bolts g^2 , inserted through said parts and engaging washer-plates g^3 , mounted upon the inner sides of the contacts. In order to prevent the lower or free ends of the contact-plates G^2 from yielding outwardly when brought into contact with the plates F, spring-plates g^4 are mounted upon the said contact members F and arranged to extend upwardly in position to yieldingly engage the outer surface of the plates g' , said plates being desirably and as herein shown formed by extensions of the inner supporting-plates f^7 , as indicated most clearly in Fig. 3. In order to secure a more uniform spring action, said plates g' and f^7 are divided vertically to form a plurality of independently-acting fingers.

In the operation of the switch the contact-bar E^4 is first lifted out of contact with the contacts C, and thereafter the carbon contacts are separated, while in the closing of the switch the operation is the reverse. In order to thus move the switch-lever G through the medium of the principal switch-lever E, the latter is provided with a boss e upon its upper side, which is arranged to engage a similar boss g^5 , formed upon the lower side of lever G, so that as the main lever is oscillated to open the switch the auxiliary lever will remain stationary until the two lever-arms are brought into contact, after which the lever G will be carried forward positively with the main lever.

The switch is adapted to be thrown open automatically by means of a spring, which is conveniently and as shown in the present instance made in the form of a coiled contractile spring H, one end of which is attached to

the center of the bar d' , which unites the switch-lever standards, while its opposite end is attached to a part of the lever E located above the pivotal axis of the latter, so that 5 the tension of the spring tends to lift or throw over the lever. Conveniently such attachment is formed by passing the looped end of the spring through an aperture i , formed through an integral web e' , extending between the arms of the lever. The limit of throw of the lever is determined by means of suitable stops or shoulders d'' , which, as shown herein, consist of rubber blocks seated in suitable sockets d'' , formed in the upper 10 parts of the standard members and located in the path of movement of the arms g of the auxiliary switch-lever G. In order to hold the switch-levers in open position frictionally, spring-blades d'' are secured to the standards 15 in position to embrace and bear yieldingly against the sides of said arms g when the latter are in their forward position.

The switch is normally held in closed position and against movement under the influence of the spring H by means of a latch or 20 deterrent mechanism adapted to be operated by a solenoid. A preferred construction of this mechanism comprises a solenoid-coil I, arranged between the standard members with 25 its axis extending longitudinally of the switch, its front end terminal being connected with a stationary terminal J, projecting above the base-plate and the body of which extends downwardly through said base and forms a 30 binding-post at the lower side of the latter for engagement with one of the circuit-conductors, while the opposite terminal end of said coil is connected with one of the contact-supporting plates, as B. Desirably the solenoid- 35 coil is constructed of a plurality of strips or thin ribbons of conducting material superposed upon each other and arranged in the form of a helix, each strip extending unbroken throughout the full length of the coil, as indicated clearly in the figures of the drawings, 40 and particularly in sectional Fig. 4. Within said solenoid-coil is arranged a tubular lining or barrel k'' , within which in turn is arranged to fit and slide a solenoid-core I'. The core I' 45 is provided with an axial bore, through which is passed loosely a rod K, upon which the solenoid is adapted to reciprocate, said rod being of sufficient length to extend throughout the full length of the solenoid and outwardly 50 beyond the end of the latter a distance sufficient to accommodate the core and to project a short distance beyond the latter when it is in its outermost position. The front or outer end of the rod K is provided with a knob k, 55 which serves to limit the outward movement of the core, and is provided near its opposite end with a tappet-collar k' , adjustably secured rigidly thereon, said tappet being so located 60 that the core as it approaches the limit of its inward movement will strike against the collar

and thereafter move the rod positively with it. With the rear or inner end of the rod K is pivotally connected a link k'' , which extends rearwardly to and is connected at its opposite end with the lower end of a swinging latch l'' , the upper end of which is pivotally supported from a standard K'', mounted upon the base-plate A. The latch l'' is provided with a notch or shoulder k'' at a point intermediate of its length adapted for engagement with the toe-shaped rear end of the lever E, the arrangement being such that when the rod K is forced rearwardly by the solenoid-core the latch is oscillated through the medium of the connecting-link to release the switch-lever and permit it to be thrown upwardly under the influence of the coiled spring H. 70

J' designates a terminal substantially similar to the terminal J, the body of which extends upwardly through the base A and is 80 electrically connected with the contact-supporting plate B', this terminal constituting the means for connecting the lead or conductor of the circuit leading to the opposite pole from that connected with the terminal J. 90 When the switch is closed, the path of the current is from the terminal J through the solenoid to the contact-supporting plate B and contact C, carried thereby, thence through contact-bar E' to the opposite contact C and 95 contact-supporting plate B' and thence out through terminal J' . Without other connections it will be obvious that the entire current would be carried through the solenoid; but in order that the switch may be used for currents of various strength and at the same time so adjusted that it will be thrown open only when the strength of current exceeds the normal current for which the switch is adjusted I provide means for shunting a determined 100 proportion of the current around the solenoid. To this end I provide a series of conductor-bars L, each adapted to be connected with and extend from the terminal J beneath the base-plate to a similarly-constructed binding-post J'' , located beneath the contact-supporting plate B and arranged to extend up through the base and forming electrical connection with said plate. Said conductor-bars as a whole are desirably comprised of one or 105 more straps or bars l, united at their ends with nut-shaped sockets or collars l', adapted to fit upon the terminals J and J'' , the several units of each conductor-bar (when the latter is composed of more than one) being each 110 made of the same definite carrying capacity, so that the operator may know at a glance what proportion of the current will be carried through the shunt-circuit of the switch. Obviously by simply substituting conductor-bars having different numbers of units the 115 switch may be adjusted to open at any desired strength of current.

The operation of the switch has been sufficiently indicated in connection with the de- 120

65 125 130

scription and need not, therefore, be again detailed. It may be noted, however, that in use the switch will ordinarily be secured with the base in a vertical position, that end of the 5 switch which for convenience of description has been herein designated as the "rear" end being placed uppermost, so that the core of the solenoid will normally rest against the knob at the lower end of the rod K and will 10 be drawn up against the force of gravity by magnetism when the solenoid is energized to the required degree.

It will be noted that by reason of the peculiar construction and arrangement of the 15 main or laminated contact devices not only will the yielding leaves or laminæ adapt themselves to any inaccuracies of adjustment or construction of the contact-bar, but each of said leaves will come into contact with said 20 bar with a slightly rubbing or sliding movement, so that the contact-surfaces will be kept bright and in most efficient condition.

The feature of supporting one of each pair 25 of the carbon contacts so that it may yield bodily and at the same time oscillate upon its bearings is obviously an important one, inasmuch as it insures that the meeting faces of the contact devices shall rest squarely against each other throughout the entire opening and 30 closing movement of the contact regardless of whether or not the movable member is so mounted as to move accurately into engagement with the fixed member. It will be furthermore obvious that the advantageous results 35 due to thus mounting a pair of contacts are not confined to carbon contacts or contacts of equivalent material; but, on the contrary, this mode of mounting is applicable to contacts of any conducting material, with similar 40 advantageous results.

While I have herein shown and described a preferred embodiment of my invention, yet it will be obvious that the invention may be otherwise embodied without departing from 45 the principles of the same, and I do not, therefore, wish to be limited to the details shown herein except as made the subject of specific claims.

I claim as my invention—

50 1. In an electric switch, the combination of a fixed contact device and a relatively movable contact device, each provided with a flat meeting face of extended area and adapted to contact with each other, one of said contacts being pivotally supported upon a spring-pressed arm, said pivotal engagement being arranged at a point intermediate of the contact length of the contact device and the axis of the pivot being arranged to extend parallel with, and 55 transversely to the contact-surface of the device, whereby the contact device is permitted to yield bodily under pressure of the opposing contact device and to oscillate into position to rest squarely against said opposing 60 contact, and a second yielding support con-

nected with a part of the contact remote from the pivot-support and whereby it is held yieldably in a determined position.

2. In an electric switch, the combination of a fixed carbon contact-block and a relatively movable carbon contact-block, each provided with a flat contact-face of extended area, one of said contacts being pivotally supported upon a spring-pressed arm and having its pivotal connection arranged at a point intermediate the length of its contact-face and with its pivotal axis extending parallel with, and transversely to, said contact-face, whereby the contact-block is permitted to yield bodily under pressure of the opposing block and to oscillate into position to rest squarely against said opposing block, and a second support connected with a part of the contact remote from the pivotal axis, consisting of a U-shaped spring, whereby said contact-block is held 75 yieldably in a determined position so as to insure a rubbing engagement throughout the opening and closing movement of the contacts.

3. In an automatic circuit-breaker, the combination of a base carrying a stationary contact, a spring-actuated lever device carrying a movable contact, a pivotally-supported latch engaging the lever device and holding its contact in contact with the stationary contact, circuit devices, and a solenoid device adapted 90 to unlatch the lever device upon the passage of an abnormal current, said solenoid device consisting of a coil having a slidable tubular core, a rod extending through said core and beyond its ends, said rod being provided with 95 a tappet-collar at each end beyond the core, and a link pivotally connecting one end of said rod to the free end of the aforesaid latch, for the purposes set forth.

4. In a circuit-breaking device, the combination of a pair of flat-faced carbon contact-plates adapted to overlap and slide off and onto each other, one of these plates being movable with respect to the other, means for supporting the stationary contact-plate so that it may be oscillated and will be spring-pressed toward the other contact-plate, said means consisting of a yielding support at one end of the plate and a pivotal support connected to it at a distance from said yielding support.

5. In combination with a base, a stationary carbon contact-plate, means yieldingly connecting one end of said contact to said base, so that it may be oscillated with respect to the base, one or more spring-clasps g^1 connected 110 to said contact-plate at its point of connection to the base, a lever device carrying a companion carbon contact-plate adapted to overlap said stationary carbon contact-plate and fit between the spring-clasps and the contact-face of 115 the stationary contact-plate, for the purposes set forth.

6. In an electrical circuit-breaker, the combination of a support and a member movable with respect thereto, a contact-plate carried 120

by the support and another contact-plate carried by the movable member, said contact-plates being adapted to overlap and slide onto and off each other to make and break the circuit, means for yieldingly and oscillatingly supporting one of the contact-plates, for the purpose set forth, and one or more spring-clasps carried by one of the contact-plates and extending over and clasping the other contact-plate, whereby the two contact-plates will be held in close contact while overlapped.

7. In an electrical circuit-breaker, the combination, of a support and a member movable with respect thereto, a contact-plate carried by the support and another contact-plate carried by the movable member, said contact-plates being adapted to overlap and slide onto and off each other to make and break the circuit, means for yieldingly and oscillatingly supporting one of the contact-plates, for the purpose set forth, and one or more spring-clasps carried by this latter contact-plate and

extending over and clasping the other contact-plate, whereby the two contact-plates will be held in close contact while overlapped. ²⁵

8. In a circuit-breaker, the combination of a base carrying a contact and circuit devices, a spring-actuated switch-lever carrying a contact, a latch engaging the lever device and holding the contacts in engagement, a solenoid in the circuit, said solenoid consisting of a coil having a slidable tubular core, a rod extending through said core and connected to said latch, said rod being provided with tappets, for the purpose set forth. ³⁰

In testimony that I claim the foregoing as my invention I affix my signature, in presence of two subscribing witnesses, this 24th day of May, A. D. 1902.
